No. 653,148.

Patented July 3, 1900.

E. OLDFIELD.

SHUTTLE.

(Application filed Sept. 30, 1899.)

(No Model.)

UNITED STATES PATENT OFFICE.

EDWIN OLDFIELD, OF NORWICH, CONNECTICUT.

SHUTTLE.

SPECIFICATION forming part of Letters Patent No. 653,148, dated July 3, 1900.

Application filed September 30, 1899. Serial No. 732,176. (No model.)

To all whom it may concern:

Be it known that I, EDWIN OLDFIELD, a citizen of the United States, residing at Norwich, in the county of New London and State of Connecticut, have invented certain new and useful Improvements in Shuttles, of which the following is a full, clear, and exact description.

This invention has for its object the improvement of the shuttles and coacting shuttle-races of narrow-fabric looms with a view to reducing the size of the shuttles, so that the smallest possible shuttle on the warp-threads is obtainable; and it also aims to simplify the construction, and thus reduce the cost of such shuttles. Heretofore it has been most common in this class of shuttles to form grooves in the opposite sides of the back portion, which grooves engage and travel on fixed ribs or ways that are mounted on the batten. At the base of one of the said grooves there is usually a toothed rack that is driven by pinion-gears in the batten in such manner that a reciprocating movement is imparted to the shuttle. This old construction cuts away and weakens the back of the shuttle, besides being more or less difficult to produce cheaply, and my present improvements are designed to overcome this difficulty in a practical and cheap way, as I shall explain.

I have illustrated my improvements in the accompanying drawings.

Figure 1 is a side elevation of a portion of a narrow-fabric-loom batten having mounted thereon suitable shuttle-supporting races and having also supported in the said races a shuttle of my newly-improved form. Fig. 2 is a cross-sectional view of Fig. 1 on line 11. Fig. 3 is an enlarged detached view of my said shuttle, and Fig. 4 is a cross-sectional view of the same on line 33 of Fig. 3. Fig. 5 is a view of said shuttle from the back side. Fig. 6 is a central sectional view of one half of the shuttle, explaining particularly the manner of chambering the same to receive the various parts. In Fig. 7 I have illustrated that portion of the shuttle-body that receives and supports the angular end of the wire on which the quill revolves.

My shuttle is made of two parts—to wit, the body-section and the back-section—the body-section being arranged to receive and

support the quill or bobbin that carries the filling-thread and having also suitable tension devices for controlling the delivery of the filling. The back-section has formed thereon peculiarly-arranged ways, and has also the rack by means of which the shuttle is driven, as I have already briefly mentioned. The body-section I cast of aluminium or other light metal that can be readily cored to provide the several necessary chambers for the reception of the tension-springs, the quill-supporting wire, &c., and when thus produced I find in practice that it is only necessary to polish the exposed parts of the said body before joining it to the back, no fitting being necessary. The back-section I also produce, preferably, of cast aluminium, although it may be made of vulcanized fiber or even of wood.

Referring now to the drawings, the letter *a* denotes the body-section, and *b* the back-section, the body being formed as a bow that provides an opening of sufficient size to receive the quill, (which latter is indicated by the letter *c*.) The bow portion *a* is cored in the operation of molding to provide chambers *a*², in which may be located tension-springs *d*, one end of each spring being secured to the back *b* and the opposite or free end being provided with a ring *d*', through which the filling is threaded. The chambers thus provided form housings to protect the springs.

*a*⁴ and *a*⁵ denote bridges that are integral with the bow *a* and extend from side to side of the shell of the latter, as is best seen in Fig. 6 of the drawings. The bridge *a*⁴ is formed with a hole *a*⁶, in which is a spiral spring *g*, and the bridge *a*⁵ has a slot *a*⁷ extending outward from its center, the said hole and slot being of a size suitable to receive the opposite ends of the wire *h*, on which the quill is revolvably mounted. Said wire has one of its ends bent at a right angle to the main or body portion, as seen in the drawings. In assembling the parts the straight end of the wire is first entered in the hole *a*⁶ and the angle at the opposite end is then pressed into the slot *a*⁷, the spring *g* meanwhile yielding as the wire enters the said hole. The spring then exerts sufficient force to prevent the accidental displacement of the wire.

In order to prevent the spring g from leaving the hole a^6 , I form an eye or loop on the inner end of the said spring and then drive a pin g' through a hole in the bridge a^4 and 5 through the said eye. This construction allows the spring to be compressed freely, but prevents the accidental displacement of said spring. Should it be desired to remove the spring to repair it or for any other purpose, 10 it is only necessary to drive out the pin g' , when the spring will drop out of the hole. I preferably solder or otherwise secure to the outer end of the spring a cap or disk g^2 , so that when the wire h is inserted in hole a^6 it 15 will have no tendency to spread the spring and cause it to bind in the hole. Bridges a^8 are also provided in the body a adjacent to the described bridges $a^4 a^5$, the opening at the rear of each bridge a^8 being of such size that 20 the spring d may pass freely therethrough, but not large enough to receive the rings d' . (See Fig. 6.) Said bridges a^8 thus serve to guide the springs and also to retain the rings in position where they may be readily grasped 25 when it is desired to thread the shuttle.

Any suitable tension device or "drag" 30 may be provided to prevent the quill from rotating too freely. As here shown, the said drag consists of a wire k , mounted in the opposite ends of the body a , near the back-section b , and having a spring-controlled radial arms k' , whose free end bears against the quill; but this particular device forms no part of my present invention.

The back-section b of my improved shuttle 35 is secured to the body-section by rivets or screws m and is formed at its opposite edges with ribs $b' b^2$, that extend beyond the body-section and serve, in connection with corresponding grooves $s s'$ in the batten, as ways 40 to guide the shuttle as it travels forward and backward in the said batten. The way b' is offset from the inner face of the back-section, thus providing an angle b^3 , which serves when 45 the back and body are being assembled as a stop and guide to properly locate the back on the body, and also serves in the finished shuttle as a retaining-rib to keep the two parts at all times in proper relation to each 50 other. This particular form of back locates the guide-rib b' well inward—that is to say, toward or overlapping the body-section—and makes it practical to cut away the adjacent outer portion of the back, so that the rack b^4 55 may be located very close to the body-section. I am thus able to narrow up the shuttle materially, and by so doing a considerably-less harness action and consequent shed on the warp is necessary.

In casting the body-section a I provide two or more stud-like projections a' on the ends that are to abut the back-section, and when

finishing the said back-section I provide therein holes that register with and receive the said projection a' . The backs are finished 65 in "jigs," so that they are all alike, and I am thus able to assemble the two parts of the shuttle and secure them together with practically no fitting of the parts.

Lugs a^9 are cast on the body a , and said 70 lugs are drilled to receive the screws or rivets m , by means of which two shuttle parts are secured together. (See Fig. 6.)

The raceways in which the described shuttle travels consist of grooves $s s'$, formed in 75 the batten n , these grooves being offset from each other to correspond with the offset ribs $b' b^2$ on the shuttle-back, and it will be noticed that when the shuttle is mounted in the grooves $s s'$ the lower rib b' is located very 80 near the gravity center of the shuttle and bears the major part of the weight of the shuttle, thus overcoming in a large degree the friction resistance that is always present in shuttles that are supported at or near the 85 extreme edge of the back-section.

My described shuttle has the desirable advantages of light weight and cheapness of construction, and I also find in practice that they may be readily repaired when either of 90 the parts (body or back) become worn or broken.

I claim as my invention—

1. A shuttle for narrow-fabric looms consisting, in combination, of a body-section having spring-receiving chambers, and a back-section formed with a rack and with offset guide-ribs that lie within the outer or rear face of the said rack.

2. In combination, in a shuttle, a rack-section, and a bow-shaped body-section consisting of a cast-metal shell having spring-receiving chambers and bridges a^4, a^5 and a^7 , substantially as specified.

3. In combination, in a shuttle, a bow-shaped body-section consisting of a cast-metal shell having spring-receiving chambers and bridges $a^4 a^5 a^8$, as set forth, and a back-section having a central rack and offset ribs, substantially as specified.

4. In a shuttle, in combination, a bow-shaped body-section consisting of a cast-metal shell having a chambered bridge a^4 and an oppositely-located slotted bridge a^5 , as set forth, a spring within the bridge a^4 and a pin 115 extending transversely through the inner end of the said spring for the purpose specified.

Signed at Norwich, Connecticut, this 18th day of September, 1899.

EDWIN OLDFIELD.
